Primary Examiner — Brian N Vinson(74) Attorney, Agent, or Firm — Stinson Morrison Hecker LLP(57) CLAIM

The ornamental design for a corner organizer, as shown and described.

DESCRIPTION

FIG. 1 is a front perspective view of the corner organizer;
 FIG. 2 is a front elevational view of the corner organizer of FIG. 1;
 FIG. 3 is a rear elevational view of the corner organizer of FIG. 1;
 FIG. 4 is a left elevational view of the corner organizer of FIG. 1;
 FIG. 5 is a right elevational view of the corner organizer of FIG. 1;
 FIG. 6 is a top plan view of the corner organizer of FIG. 1; and,
 FIG. 7 is a bottom plan view of the corner organizer of FIG. 1. The broken lines shown in the drawings form no part of the claimed design.
